SUBSTATION LOCKING APPARATUS

Herbert F. Obergfell, deceased, late of River Forest, Ill., by Amanda Obergfell, executrix, River Forest, Ill., assignor to Automatic Electric Laboratories, Inc., Chicago, Ill., a corporation of Delaware

Application March 4, 1944, Serial No. 525,019

2 Claims. (Cl. 179—100)

1

This invention relates in general to improvements in substation locking apparatus, but is particularly concerned with an improvement in the switching mechanism in the telephone set.

In telephone sets of the present type it has been the usual practice to operate the switching contacts by lifting the hand set from its rest or holder which would cause an operating plunger or button to move and operate contacts to switch the substation circuits from a signalling to a talking position.

Applicant's invention consists in the provision of an arrangement of the switching mechanism, controlled by the hand set, so that it is normally locked against operation and can only be operated after the removal of the hand set from its support, by a manual operation to release the locking device.

The invention is an improvement over the type of switch shown in Obergfell Patent No. 2,133,468, issued October 18, 1938.

The one sheet of drawings comprising Figs. 1-6 inclusive, taken in connection with the following detailed description is believed to be sufficient to make the invention clear.

Fig. 1 is a perspective front view of a wall telephone illustrating my invention and showing a hand set on its support held by spring clips.

Fig. 2 is an enlarged detailed side view of one of the wire spring clips shown in Fig. 1. These clips tend to prevent displacement of the hand set.

Fig. 3 is a front view of the switch mechanism showing the switch mechanism and locking device in normal position, and showing only a partial section of the support on which it is mounted.

Fig. 4 is a bottom view of Fig. 3, also showing the switch mechanism and locking device in normal position also showing only a section of the self support.

Fig. 5 is a view taken from the back of Fig. 4 showing the switch mechanism as a unit separate from its mounting bracket.

Fig. 6 is a view, partly in section, of the locking release button 17 of Figs. 1, 2 and 4 showing the details of its mounting.

Referring to the drawings the device will now be described in detail: As shown in Fig. 1 the wall telephone has a projecting shelf support 1 within which the switch mechanism is mounted, and upon which the hand set is supported to operate the switch mechanism through the medium of the operating button 2. The switch as shown in Figs. 3 and 4 is mounted on the end 55

2

portion of the bracket 3 of which only a part is shown. The bracket 3 is fastened at one end to the wall phone by means not shown. The bracket 3 is also fastened to the shelf of the telephone by the bushing 4 of the operating button 2, which is inserted through a hole in the shelf and screwed to bracket 3, thereby clamping the bracket 3 to the shelf. The switch as shown in Figs. 3, 4 and 5 comprises a metal plate 5 secured to bracket 3 by screws 6 and 7. The metal plate 5 supports a pair of arms 8 and 8' as shown in Figs. 3 and 4 extending downward and supporting the spring combinations 9 and 9'. A stop 10 is formed out of plate 5 and extends downward to limit the movement of the lever 13. A pair of ears 11 as shown in Fig. 3 and 4 extending downward from the plate 5 provide a support for the pivot pin 12 for hinging the lever 13 which is provided with a pair of insulated bushings 14 for actuating the two sets of spring combinations 9 and 9'. The tension stored in the spring combinations 9 and 9' tends to move the lever 13 upward (as seen in Fig. 3) toward the plate 5.

Also supported by plate 5 is the locking arm 15 which consists of a flat metal member held against the underside of plate 5 by means of the mounting screw 6. The mounting screw 6 has a shoulder which goes through a hole in the locking arm 15 and this screw also fastens the plate 5 securely to the bracket 3, leaving the locking arm free to pivot around the shoulder. The locking arm 15 has one arm extending upward as seen in Fig. 4 having a downwardly turned ear 16 which lies directly in front of the inner end of button 17. The arm 15 also has an extended portion having the downwardly turned ear or stop 18 which in normal position acts as a stop to hold lever 13 in its normal position as shown in Fig. 3. The whole arm is rotatable about screw 6 as its pivot and has a spring 19 normally tending to hold it in the position shown in Figs. 4 and 5. This tension spring 19 as shown in Fig. 4 hooks on the side of one of the supporting arms 8 and goes upwardly at an angle to the opposite side of the other supporting arm 8' and then bends at an angle to the left around said arm 8' and fits in a groove in the tension spring guide 20. The tension spring guide 20 is securely fastened to the arm 15 adjacent to the ear 16. Also securely fastened to the locking arm 15 is the stop 21 which consists of a pin extending out from the lower surface of arm 15 as shown in Figs. 4 and 5. This stop allows the locking arm 15 to move only the distance determined by the sides of the opening 22 in plate 5. The

button 17 moves inside a bushing 23 as shown in Fig. 6 which is fastened to the shelf 1 by the nut 24.

The switch is held in a normal position when the hand set is removed from the operating button 2 by the locking arm 15 as shown in Figs. 3, 4 and 5. To permit operation of the switch the release button 17 is manually operated. The release button 17 presses against the ear 16 of the locking arm, opposing the force of the tension spring 19, and moves the locking arm 15 downward as seen in Fig. 4. This will cause the stop 18, which normally prevents lever 13 from operating when the hand set is removed from the operating plunger, to slide off of the surface of lever 13. The lever 13 due to the tension of the springs on the bushings 14 will now operate and move the button 2 upwards. The movement of lever 13 allows the switching springs 9 and 9' to operate and switch the telephone circuits from a signalling to a talking position.

With the switch in an operated position the stop 18 rests against the side of lever 13. When the hand set is placed on the operating plunger 2 the lever 13 moves downward until it hits stop 10. This movement of lever 13 releases stop 18 and the tension spring 19 will operate the locking arm 15 to its initial position to lock the spring mechanism in normal position again.

This locking mechanism prevents the switching contacts from operating when the hand set is removed. It also prevents false impulses from being sent over the line by the jarring or jiggling of the hand set upon its removal from the support.

In addition to the locking mechanism just described a pair of wire spring clips are provided to hold the hand set in normal position. The pair of wire spring retaining clips 25 shown in Figs. 1 and 2 are pivotally mounted in the cradle of the wall phone and tend to hold the hand set in place. Each wire spring clip is bent substantially U-shaped with an eyelet 27 on the front leg to provide a pivot point for the clips. These spring clips fit in grooves cut in the cradle, and a coil spring 26 is fastened to the rear leg of each spring clip to hold the clips in place. The hand set is removed from the cradle by pulling it forwardly against the tension of the springs 26 attached to the rear legs of the clips until the front legs of the clips strike the ends of the slots in the cradle and further forward movement of the hand set thereafter separates the two legs of the clips sufficiently to permit complete withdrawal of the hand set.

While the invention has been described as embodied in a particular form, it is capable of employment in other and different forms without departing from the spirit and scope of the appended claims.

What is claimed is:

1. In a telephone set, a hand set, a support therefor, switching springs inside the telephone set, a first button extending through the support

and engaged at one end by the hand set when placed on said support, a lever for operating said springs engaged by the other end of said button, a flat metal locking arm inside said set with ears extending at right angles to the arm, a spring normally maintaining one of said ears in engagement with said lever to prevent operation of said lever and said switching springs when the hand set is removed from said support, and a second button normally engaging the other ear of said locking arm manually operative for operating said locking arm to permit operation of said lever and said switching springs.

2. In a hand set telephone, a support for the hand set, switching springs in said telephone, a lever operated by placing the hand set on its support for tensioning said springs, a pivotal flat locking member inside said support and having a normal locking position, an integral extending first arm of said locking member normally engaging said lever in said locking position for locking said lever against movement when the handset is removed from said support, an integral extending second arm of said locking member having the outer end turned at right angles thereto, spring means in said support engaging said outer end of said second arm for normally holding said locking member and said first arm in said locking position when said hand set is removed from its support, and a push button means manually operated to engage said outer end of said second arm and move said locking member and said first arm from said locking position against the tension of said spring means, said tension of said switching springs moving said lever in response to said movement of said member and said first arm from said locking position after said hand set has been removed from said support.

AMANDA OBERGFELL,
*Executrix of the Estate of Herbert F. Obergfell,
Deceased.*
